UNITED STATES PATENT OFFICE

EWEN HENRY SMITH, OF BELFAST, IRELAND, ASSIGNOR TO WORKMAN CLARK (1928) LIMITED, OF BELFAST, IRELAND

HEATING AND SUPPLY OF FEED WATER IN STEAM POWER PLANTS

Application filed March 14, 1930, Serial No. 435,703, and in Great Britain May 30, 1929.

This invention relates to steam power installations and more particularly to the feed water supply therein.

In steam power installations there is always a certain loss of water and therefore the feed water derived from condensation of the steam requires to be supplemented.

The object of the present invention is to provide improvements in the heating and supplementing of the feed water.

According to this invention, a steam power installation comprises one or more feed water heaters heated by steam drawn from the main steam circuit, and an auxiliary steam generating plant heated by means independent of the main generating plant and its heating means, a feed heater in series with the first mentioned heater or heaters and supplied with live steam directly from the said auxiliary generating plant and means for adding the condensate from the last mentioned heater to the feed water to make up for losses of water occurring in the installation.

The use of steam in this way for heating allows of the final temperature of the feed water being kept constant under different working conditions.

In order that the invention may be clearly understood one embodiment thereof in conjunction with a steam turbine will be described by way of example and with reference to the accompanying drawings wherein:

Fig. 1 is a diagrammatic view illustrating the invention,

Fig. 2 is a sectional elevation showing, by way of example, a type of feed heater which may be employed, and

Fig. 3 is a sectional plan on the line III-III in Fig. 2.

On the drawings the numeral 1 denotes a steam turbine supplied with steam from steam generator 2 and exhausting into a condenser 3 whence the condensate is drawn off by an air pump 4 into a hot well 5.

A series of feed heaters (in this case two in number) 6, 7 are located in series in the feed main 8 leading from the hot well 50 through a feed pump 9 to the generator 2.

The feed heater 6 is supplied with steam as a heating agent from the turbine through a pipe 10 and has a drain 11 connecting it to the hot well 5. The feed heater 7 has a pipe 12 supplying it with steam from a different stage of the turbine and has a drain 13 connecting it to the feed heater 6 and thence to the drain 11 and hot well 5.

In addition to the feed heaters 6 and 7 a third feed heater 14 is interposed between the feed heater 7 and the steam generator 2.

As shown in Figs. 2 and 3, the heater is of usual design comprising a casing 25 in which is inserted a lower floating header 26 connected by water tubes 27 to an upper header 28. The headers 26, 28 are so partitioned that feed water entering at the inlet 29 will flow four times along the length of the header, as indicated by arrows in Fig. 2, before passing out at outlet 30. The heating steam enters at 31 and circulates round the water tubes 27 and the condensate passes out at the drain 32 to the preceding heater or to the hot well. The heater as shown would be used as the heater 14 in Fig. 1, while for use as heater 6 or 7 an inlet for the condensate from the succeeding heater would be provided on the casing 25.

The flow of the condensate in the drains 18 and 13 is caused by the difference in pressure of the steam used in the heaters. Drains 13 and 18 are so arranged that a water seal exists in them thereby ensuring that only condensate will pass from one heater to another. This arrangement provides that all the latent heat of the steam will be extracted in the appropriate heater while the sensible heat of the condensate will be extracted in the preceding heater to which the condensate, as above mentioned, will be caused to flow by the difference in steam pressure in the heaters.

All three of the feed heaters are provided with conventional controlling and cut out valves.

The numeral 15 denotes an auxiliary steam generator which is connected by a steam pipe 16 through valve 17 to the feed heater 14 from which a drain 18 leads into the feed heater 7 and thence to the hot well 5.

An auxiliary hot well 19 is provided to receive the exhausts or drains from auxiliary supplies through the pipe 20. This auxiliary hot well is connected by an auxiliary feed pipe 21 to the auxiliary generator 15 into which latter feed water is pumped by the auxiliary feed pump 22. Additional water to feed the auxiliary generator 15 is fed through a valve controlled pipe 25 from a reserve tank 10 or tanks (not shown).

An overflow pipe 23 terminating at a certain height above the bottom of the main hot well 5 leads into the auxiliary hot well which is located at a lower level than the main hot well.

The pipe 24 is a connection from the auxiliary generator for auxiliary supplies.

The function of the installation is as follows:—

26 The feed heater 14 is arranged to raise the temperature of the fed water through the final stage necessary to bring it up to the temperature at which it is desired to feed the generator 2 and this heating is effected by 25 live steam direct from the auxiliary generator 15. The steam utilized in the feed heater 14 passes out through the drain 18 and by way of feed heater 7, drain 13, feed heater 6 and drain 11 into the main hot well 5 so that it 30 supplements the normal feed water and makes up for losses of water in the system. The capacity of the heater 14 is so arranged that the condensed heating steam which forms the drain will provide the necessary 35 supplementary feed for the main generator in ordinary working.

At reduced power the temperature of the steam drawn from the turbine for heating purposes in the feed heaters 6 and 7 is reduced but the heater 14 will enable the feed 40 temperature to be maintained at a standard level owing to its being supplied independently from the auxiliary generator. Should however the quantity of condensed steam 45 supplied to the feed water from the auxiliary generator exceed the quantity of supplementary feed required under any particular working conditions, surplus will overflow through the overflow pipe 23 from the main 50 hot well to the auxiliary hot well.

The invention may be subject to numerous variations to adapt it for embodiment in steam power installations of various types, e. g., land or marine installations and installations having reciprocating or turbine machinery.

I claim:—

1. A steam power installation comprising an engine, a main steam generating plant, 60 an auxiliary steam generating plant fired independently of the main steam generating plant, feed water heating means for the latter, means for heating the feed water heating means partly by steam drawn from the main 65 generating plant and partly by live steam

direct from the auxiliary generating plant and means for adding the condensate of said steam from the auxiliary generating plant to the feed water to make up for losses of water occurring in the installation.

2. A steam power installation comprising an engine, a main steam generating plant, feed water heating means supplied with steam from the main steam generating plant, means for heating the main steam generating plant, an auxiliary steam generating plant, a second heating means independent of the first mentioned heating means for heating the auxiliary generating plant, additional feed water heating means in series with the first mentioned feed water heating means and supplied with live steam directly from the auxiliary generating plant, and means for adding the condensate of the steam from the additional feed water heater to the feed water for the main steam generating plant.

3. A steam power installation comprising an engine, a main steam generating plant, means for heating the same, a plurality of feed water heaters, a steam supply thereto from the main generating plant, a hot well for the collection of condensate, a drain connection between the feed water heaters and the hot well, an auxiliary steam generating plant, a second heating means independent of the first mentioned heating means for heating the auxiliary generating plant, an additional feed water heating means connected for the supply of live steam direct from the auxiliary generating plant for heating purposes and a drain connection between said additional feed water heating means and the hot well through which the condensate therefrom is added to the feed water.

4. A steam power installation comprising an engine, a main steam generating plant, means for heating the same, a plurality of feed water heaters, a separate steam supply connection to each from the engine, a hot well, a drain connection between the first feed water heater and the hot well, a drain connection from each remaining heater to the first and thence to the hot well, an auxiliary steam generating plant, a second heating means independent of the first mentioned heating means for heating the auxiliary generating plant, an additional feed water heating means connected for the supply of live steam direct from the auxiliary steam generating plant for heating purposes, and a drain connection between said additional feed water heating means and the hot well through which the condensate therefrom is added to the feed water.

5. A steam power installation comprising an engine, a main steam generating plant, feed water heating means supplied with steam from the main steam generating plant, an auxiliary steam generating plant fired independently of the main steam generating

plant, additional feed water heating means in series with the first mentioned feed water heating means and supplied with live steam directly from the auxiliary generating plant, 5 and means for adding the condensate of the steam from the additional feed water heating means to the feed water for the main steam generating plant.

6. A steam power installation comprising 10 an engine, a main steam generating plant, a plurality of feed water heaters, a steam supply thereto from the main generating plant, a hot well for the collection of condensate, a drain connection between the feed water 15 heaters and the hot well, an auxiliary steam generating plant fired independently of the main steam generating plant, an additional feed water heating means connected for the supply of live steam direct from the auxiliary 20 generating plant for heating purposes, and a drain connection between said additional feed water heating means and the hot well through which the condensate therefrom is added to the feed water.

25 7. A steam power installation comprising an engine, a main steam generating plant, a plurality of feed water heaters, a separate steam supply connection to each from the engine, a hot well, a drain connection between 30 the first feed water heater and the hot well, a drain connection from each remaining heater to the first and thence to the hot well, an auxiliary steam generating plant fired independently of the main steam generating 35 plant, an additional feed water heating means connected for the supply of live steam direct from the auxiliary steam generating plant for heating purposes, and a drain connection between said additional feed water 40 heating means and the hot well through which the condensate therefrom is added to the feed water.

8. A steam power installation comprising 45 an engine, a main steam generating plant, feed water heating means supplied with steam from the main steam generating plant, a main hot well for the collection of condensate, a drain connection between the feed water heating means and the hot well, an auxiliary steam generating plant fired independently of the main steam generating plant, an additional feed water heating means connected for the supply of live steam direct from the auxiliary steam generating plant 55 for heating purposes, a drain connection between said additional feed water heating means and the hot well through which the condensate therefrom is added to the feed water and an auxiliary hot well serving the 60 auxiliary steam generating plant and connected with the main hot well to receive any overflow from the latter should the supply of condensate from the auxiliary generating plant exceed the quantity of feed water 65 required to be made up.

9. A steam power installation comprising an engine, a main steam generating plant, a plurality of feed water heaters, a steam supply thereto from the main generating plant, a main hot well for the collection of condensate, a drain connection between the feed water heaters and the hot well, an auxiliary steam generating plant fired independently of the main steam generating plant, an additional feed water heating means connected for the supply of live steam direct from the auxiliary generating plant for heating purposes, a drain connection between said additional feed water heating means and the hot well through which the condensate therefrom is added to the feed water, and an auxiliary hot well serving the auxiliary steam generating plant and connected with the main hot well to receive any overflow from the latter should the supply of condensate from the auxiliary generating plant exceed the quantity of feed water required to be made up. 70 75 80 85

10. A steam power installation comprising an engine, a main steam generating plant, a plurality of feed water heaters, a separate steam supply connection to each from the engine, a hot well, a drain connection between the first feed water heater and the hot well, a drain connection from each remaining heater to the first and thence to the hot well, 90 an auxiliary steam generating plant fired independently of the main steam generating plant, an additional feed water heating means connected for the supply of live steam direct from the auxiliary steam generating plant for heating purposes, a drain connection between said additional feed water heating means and the hot well through which the condensate therefrom is added to the feed water, and an auxiliary hot well serving the auxiliary steam generating plant and connected with the main hot well to receive any overflow from the latter should the supply of condensate from the auxiliary generating plant exceed the quantity of feed water required to be made up. 95 100 105 110

In testimony whereof I affix my signature.
